G. E. OLSEN,

APPARATUS FOR CLEANING AND PURIFYING USED GASOLENE, NAPHTHA, OR THE LIKE.
APPLICATION FILED JULY 26, 1915.

1,199,491.

Patented Sept. 26, 1916.

Fig. 1.

A detailed line drawing of a wooden structure, possibly a small building or a porch. It features a door with the number '51' and a window with the number '50' on its frame. The structure is surrounded by a railing. To the right of the drawing, the text 'FIG. 4. George E. Olsen' is written above 'By his attorney, Walter D. Godding.' Below this, a circular stamp is partially visible, containing the text 'Walter D. Godding' and 'Attala Co., MS'.

UNITED STATES PATENT OFFICE.

GEORGE E. OLSEN, OF GREEN BAY, WISCONSIN, ASSIGNOR TO TROY LAUNDRY MACHINERY CO., LTD., OF CHICAGO, ILLINOIS, A CORPORATION OF NEW YORK.

APPARATUS FOR CLEANING AND PURIFYING USED GASOLENE, NAPHTHA, OR THE LIKE.

1,199,491.

Specification of Letters Patent. Patented Sept. 26, 1916.

Application filed July 26, 1915. Serial No. 41,843.

To all whom it may concern:

Be it known that I, GEORGE E. OLSEN, a citizen of the United States, residing at Green Bay, in the county of Brown and 5 State of Wisconsin, have invented new and useful Improvements in Apparatus for Cleaning and Purifying Used Gasolene, Naphtha, or the like, of which the following is a specification.

10 This invention relates to improvements in apparatus for cleaning and purifying used gasoline, naphtha or the like.

The object of the invention is to provide a simple and economically operated apparatus for thoroughly washing and rinsing used gasoline or naphtha with a clean, fresh liquid preferably water, after which said gasoline is concentrated in suitable compartments and separated from the cleansing 20 liquid.

Another object of the invention is to provide an automatic shut off valve which will remain open during the removal of the cleaned liquid, but which will be closed by 25 the approach of the cleansing liquid thereto, thereby preventing any of the water or dirt, which has previously been removed from the gasoline or naphtha, from mixing with the purified liquid.

30 The invention consists in the combination and arrangement of parts set forth in the following specification and particularly pointed out in the claims.

Referring to the drawings: Figure 1 is a 35 side elevation, partly in section, of an apparatus embodying my invention. Fig. 2 is a sectional view of the automatic shut off valve. Fig. 3 is a plan view of one of the receivers illustrated in Fig. 1. Fig. 4 is a 40 detail sectional view of the compartment at the upper end of one of the receivers illustrating a modified form of automatic shut off valve.

Like numerals refer to like parts throughout the several views of the drawings.

In the drawings, 5 and 6 represent two receivers or tanks which are preferably practically of the same construction, the tank or receiver 5 constituting a washer for used 50 gasoline or naphtha which is supplied from

the dry washing apparatus. The receiver 6, which as has been hereinbefore stated, is substantially of the same construction as the receiver 5 and is connected with said receiver 5 and constitutes a rinser for the gasoline or naphtha after it has been passed through the receiver 5. 55

The pair of receivers 5 and 6 embody the preferred number of receivers employed in the washing of gasoline or naphtha in accordance with my invention. It is however perfectly obvious that others may be added to the series or one receiver may be employed without departing from the spirit and scope of the invention. Each of the receivers 5 and 6 is preferably provided with agitators 60 65 7, 7 consisting of a rotary vertical shaft 8 journaled to rotate in bearings 9 and 10 in the bottom and top sections of the receiver. A series of blades 11, preferably inclined, 70 are secured to the shafts 8. The agitators 7 are preferably arranged at right angles to each other in order that they may not occupy too much of the space within the receiver 5 and to more thoroughly agitate the 75 liquid contained within said receiver.

The two shafts 8, 8 are arranged to be rotated simultaneously by mechanism suitably arranged preferably at the top of the receiver 5, said mechanism preferably consisting of a shaft 12 having gears 13, 13 fast thereon adapted to engage pinions 14, 14 secured respectively to the shafts 8. A driving pulley 15 is secured to the shaft 12. The receivers 5 and 6 are adapted to contain 85 a cleansing liquid which is preferably water and the liquid to be cleaned, such as gasoline, naphtha or other kinds of oil.

To supply the water to the receiver 5 a water supply pipe 16 has been provided 90 which preferably enters the bottom of said receiver and terminates in a curved pipe 17, the discharge end thereof being directed toward the bottom of said receiver and in close proximity thereto. An oil supply medium 18 95 is provided for the receiver 5 preferably connecting said receiver adjacent to the highest point in said receiver.

The receiver 5 further embodies in its construction a compartment 19 which is dis- 100

posed at the upper end of said receiver and is substantially smaller in diameter than the main or body portion of said receiver, said compartment being for the purpose of concentrating the cleaned liquid previous to its being discharged from said receiver and to said compartment the oil supply medium is attached. An oil discharge pipe 20 is likewise connected with said concentrating compartment adjacent to the top thereof. A water or cleansing liquid discharge pipe 21 is connected preferably at the bottom of said receiver and extends upwardly along the outside of the receiver 5 to the normal water level of said receiver, said pipe being provided with a valve 22 whereby the same may be closed. A drain cock 23 is arranged in the pipe 21 below the bottom connection of said pipe with said receiver whereby all of the water within said receiver may be withdrawn when desired. A safety valve 24 is provided for the receiver 5, said valve being preferably attached to the water supply pipe 16 at a point near the lower end of said receiver. An air relief valve 25 is inserted at the top of the concentrating compartment 19 for the purpose of permitting the air in the receiver and the compartment to escape during the filling and ejecting of the oil therefrom.

The receiver 6 receives its supply of water and discharges the water therefrom in the same manner as does the receiver 5, but the oil is delivered to said receiver 6 through the discharge pipe 20 connected with the concentrating compartment 19 of the receiver 5 and another section of pipe 26.

The pipe 26 is connected to the upper end of a concentrating compartment 27 surmounting the receiver 6 as does the compartment 19 surmount the receiver 5. An oil discharge pipe 28 is provided for the receiver 6 similar to the discharge pipe 20 of the receiver 5 and connected in the same manner therewith.

Each of the receivers 5 and 6 is provided with an automatic shut off valve 29, said shut off valve being preferably arranged in said oil discharge pipes 20 and 29 respectively. A detail view of the automatic valve is illustrated in Fig. 2. The preferred arrangement or disposition of said shut off valve is within a casing or trap 30 having transparent side walls 31, the upper and lower ends of said casing being closed. The discharge pipe 20 from the concentrating compartment 19 or the discharge pipe 28 from the concentrating compartment 27 enters the trap 30 at 32. An extension 33 extends from said connecting point 32 to a point in close proximity to the bottom of said trap and directed toward said bottom. A discharge orifice 34 is provided adjacent to the top of said trap 30 through which the

oil is discharged to its proper destination, 65 that is to say, either to the rinsing receiver or tank 6 through the pipe 26 or to a suitable storage tank. The discharge of oil through the discharge orifice 34 will continue until substantially all of the oil in the 70 trap has been removed after which said valve is automatically closed.

Within the trap 30 adjacent to the discharge orifice 34 is a hollow seat 35 constructed and arranged to be engaged and 75 closed by a float 36, said float being confined within a suitable cage 37 whereby a limited vertical movement of said float will be permitted. The float 36 is heavier than oil, but lighter than water, the weight of said float 80 being adjusted by reducing or increasing the number of weights 38 attached to a screw-threaded stem 39, which stem is suspended from said float 36. Said hollow seat 35 and float 36 coöperate to form the valve 29. A 85 discharge valve 40 is arranged at the top of the trap 30 and another discharge valve 41 is provided at the bottom of said trap. A series of glass gages 42 are arranged at the 90 side of both of the receivers 5 and 6 which extend from a point below the normal water level indicated at "A" substantially to the top of the concentrating compartments 19 and 27.

The operation of the apparatus hereinbefore specifically described is as follows: Water or other suitable cleansing liquid is admitted through the pipe 16 to the tanks or receivers 5 and 6 to the level indicated at "A", or until said water begins to overflow 100 through the pipes 21, providing the valves 22 in said pipes 21 are open or if not the level "A" may be determined through the glass gages 42. The water supply is then shut off by means of the valve 43. The 105 liquid or oil to be cleansed is then admitted to the receiver 5 through the oil supplying medium 18 to a level indicated by the line "B", the oil occupying the space between the line indicated at "A" and said line "B" 110 as it is lighter than the water. The agitators 7 are now set into operation to agitate the water and oil within said tank or receiver 5 for the desired length of time during which period a greater portion of the dirt will be 115 removed from said oil. The agitators are then stopped permitting the dirt to settle in said receiver 5. Some of this dirt will be precipitated to the bottom of said receiver where it may later be withdrawn through 120 the drain cock 23. The dirt which is usually removed from the gasolene is fatty matter or grease which is considerably heavier than the oil, but remains at the surface of the water. After the dirt has had time to 125 settle, which may be determined or observed through the glass gages 42, the water supply valve 43 for the receiver 5 will again be

opened while the valves 22 for said receiver will remain closed. The pressure of the water as it enters said receiver 5 causes the oil to rise to the top of said receiver into the compartment 19 and be discharged through the discharge pipe 20 into the trap 30 between the receiver 5 and the receiver 6, said oil continuing through the pipe 26 to the tank or receiver 6. The float 36 in the trap 10 30 is lighter than the oil and permits said oil to pass uninterruptedly through said trap. This movement continues until all of the oil has been discharged from the receiver 5 or until the surface of the water reaches 15 the float 36 and moves the same upwardly against the seat 35, thereby automatically closing the discharge valve 29 and preventing any of the water in the receiver 5 from being discharged into the receiver 6. The valve 40 20 in the trap 30 is next opened permitting the discharge of all of the water which contains any of the grease, dirt or fatty matter. The valves 41 and 23 are at this time opened and all dirt which has been precipitated to the 25 bottom of the receiver 5 or trap 30 may then be removed and when all traces of dirt and grease have been removed from the water in the receiver 5, the valves 40, 41 and 43 are then closed while the valve 22 for the receiver 5 is opened and all superfluous water in said receiver permitted to escape until 30 said water has returned to its normal level, as indicated at "A". Substantially all of the dirt, grease or fatty matter will be removed 35 in the first receiver 5, but should any get by the valve 29 in the trap 30 the same operation is performed in the receiver 6 as has just been described, after which the purified oil is discharged to a suitable receiving tank 40 in readiness to be used over again and with practically no reduction in the quantity thereof from that with which it started, owing to the fact that the apparatus throughout is entirely closed to prevent any 45 evaporation or waste of said oil. By reason of the reduced diameter of the compartment 19 with respect to its receiver and likewise the compartment 27 the area of the liquid will be greatly reduced with the result that 50 all but a very small amount of the gasoline will be withdrawn before the valve 29 is closed by the rising water.

When the oil first starts to rise, due to the admittance of water into the receiver the air 55 at the top of said oil will be permitted to escape through the air relief valve 25 at the top of the compartment 19, a similar valve being provided for the compartment 27. The safety valve 24 is provided to permit 60 the water to discharge from the pipe 16 in case the valve 29 is suddenly closed and none of the outlet and discharge valves for the water have been opened.

Referring to Fig. 4, 44 represents a com-

partment similar to the compartment 19 65 which may, if desired, constitute a trap similar to the trap illustrated in Fig. 2. The upper end of said compartment 44 preferably has an opening 45 over which is placed a cover 46 and secured thereon by suitable 70 securing means such as bolts 47. Mounted in said cover is a cage 48 similar to the cage 37 illustrated in Fig. 2, said cage being perforated to permit oil to pass therethrough to a discharge pipe 49 connected to the cover 75 46. A float 50 similar to the float 36 which is capable of being lifted by water, but not by oil is arranged in said cage to coöperate with a valve seat 51 formed at the upper end of said cage and similar to the valve seat 35. 80 The float 50 and valve seat 51 constitute an automatic shut off valve similar to the one shown in Fig. 2 and capable of being operated in the same manner. A discharge pipe 52 extends upwardly from the cover 46 and 85 serves as a means whereby dirt, sediment and water may be discharged from the compartment 44 and serves in the same capacity with the pipe containing the discharge valve 40 illustrated in Fig. 2. A relief valve 53 is 90 placed at a distance above the cover 46 of the discharge pipe 52 and takes the place of the relief valve 25, as shown in Fig. 1. An oil supply pipe 54, equivalent to the oil supply pipe 18 is connected with the compartment 44 at the upper end thereof. 95

Having thus described my invention what I claim and desire by Letters Patent to secure is:

1. An apparatus of the class described 100 having, in combination, a receiver, a supplying medium for liquid to be cleaned, means constructed and arranged to agitate the liquid in said receiver, means for supplying cleansing liquid to said receiver to eject 105 the cleansed liquid therefrom, a discharge pipe for said cleansed liquid, an automatic shut off valve for said discharge pipe, and a safety valve constructed and arranged to relieve the pressure in said receiver when said 110 shut off valve is closed.

2. An apparatus of the class described 115 having, in combination, a tank adapted to contain a cleansing liquid and a liquid to be cleaned of substantially less weight than 120 said cleansing liquid, means for supplying cleansing liquid to said tank to discharge the cleaned liquid therefrom, a discharge pipe for said cleansed liquid connected with said tank adjacent to the top thereof, a trap connected with said discharge pipe constructed of transparent material, a pipe extending from said tank substantially to the bottom of said trap, a valve arranged in said trap and connected with said discharge pipe, said 125 valve comprising a float constructed and arranged to be moved by the admission of cleansing liquid into said trap to close said

valve, means constructed and arranged to vary the weight of said float, and a valve arranged adjacent the top of said trap adapted to be opened to discharge dirt and sediment from said trap.

5 In testimony whereof I have hereunto set

my hand in presence of two subscribing witnesses.

GEORGE E. OLSEN.
